SAMUEL F. CONANT, OF SKOWHEGAN, MAINE.

Letters Patent No. 76,401, dated April 7, 1868.

IMPROVED HAIR-CRIMPER.

The Schedule referred to in these Letters Patent and making part of the same.

TO ALL WHOM IT MAY CONCERN:

Be it known that I, SAMUEL F. CONANT, of Skowhegan, in the county of Somerset, and State of Maine, have invented certain Improvements in Hair-Crimpers, of which the following is a full, clear, and exact description, reference being had to the accompanying drawings, making part of this specification, in which—

Figure 1 is a perspective view, representing a pair of my improved crimpers when closed and applied to the head in a position for crimping the hair.

Figure 2 is a perspective view of one of the crimpers when open.

My invention consists in a series of spring-blades pivoted together, between which the hair, in folds, in a dry or moist state, is securely confined until crimped as desired.

To enable others skilled in the art to understand and use my invention, I will proceed to describe the manner in which I have carried it out.

In the said drawings, a series of silver-plated metallic plates, A A, &c., of the form shown in fig. 2, are pivoted together at *a*, the metal being carefully tempered, so as to possess sufficient elasticity to allow of their being bent (with the folds of hair between them) down upon each other, in which position they are retained by a hook or fastening, *b*, at the outer extremity of the upper plate A, catching over a hook, *c*, on the extremity of the under plate A. These plates serve as springs, the resistance of which, and consequently their pressure upon the hair, being increased according as the number and thickness of the folds are increased. The curvature of the under plate, from *d* to *e*, is intended to be made to conform to that of the portion of the head to which the crimper is to be applied, but may be readily bent by the fingers to a different curvature, to fit more snugly, if required.

The hair may be moistened previous to being crimped, or it may be crimped when dry or in its natural state; but I prefer to use the crimper when the hair is moist, as it may then be drawn more smoothly over the several inner plates A, a comb being sometimes used in the operation.

The party whose hair is to be crimped may, with or without the aid of a looking-glass, perform the operation in a very ready and satisfactory manner, one of the crimpers remaining upon each side of the parting-line or other portion of the head, until the hair is pressed and bent sufficiently to remain "set" in the position desired.

As the crimpers are intended to be used in pairs, they are made "symmetrical;" that is, one is made specially for the right side of the "part," while the other is made for the left side, the pivoted ends being placed toward the back of the head.

The front or upper plate A may be of any form desired, and may be ornamented, to give the crimper a unique appearance; and the several plates may be of greater or less width, according to the style of crimping desired.

In the foregoing description I have spoken of the crimpers being made of metal, but I find rubber will answer well; consequently I do not limit myself to any particular material; and the several plates may be hinged together, so as to be lifted up in a vertical direction, instead of swinging upon each other horizontally, without departing from the spirit of my invention.

Claim.

What I claim my invention, and desire to secure by Letters Patent, as an improvement in "hair-crimpers," is—
The series of spring-plates A A, pivoted together, substantially as described.

SAMUEL F. CONANT.
